(57) **CLAIM**

We claim the ornamental design for a product dispenser, as substantially shown and described.

DESCRIPTION

FIG. 1 is an elevated perspective view of a product dispenser of the present invention.

FIG. 2 is a level view of a front side of the product dispenser of the present invention.

FIG. 3 is a level view of a rear side of the product dispenser of the present invention.

FIG. 4 is a level view of a right side of the product dispenser of the present invention.

FIG. 5 is a level view of a left side of the product dispenser of the present invention.

FIG. 6 is a top plan view of a top side of the product dispenser of the present invention.

FIG. 7 is a bottom-up view of a bottom side of the product dispenser of the present invention.

FIG. 8 is an elevated perspective view of a variant of the product dispenser of the present invention.

FIG. 9 is a level view of a front side of the variant of the product dispenser of the present invention.

FIG. 10 is a level view of a rear side of the variant of the product dispenser of the present invention.

FIG. 11 is a level view of a right side of the variant of the product dispenser of the present invention.

FIG. 12 is a level view of a left side of the variant of the product dispenser of the present invention.

FIG. 13 is a top plan view of a top side of the variant of the product dispenser of the present invention; and,

FIG. 14 is a bottom-up view of a bottom side of the variant of the product dispenser of the present invention.
